(57) **CLAIM**

The ornamental design for an external housing of an LED-based linear lighting apparatus, as shown and described.

DESCRIPTION

FIG. 1 is a top perspective view of the external housing of an LED-based linear lighting apparatus showing the new design; FIG. 2 is a bottom perspective view thereof;

FIG. 3 is a front view thereof;

FIG. 4 is a side view thereof;

FIG. 5 is a top view thereof; and,

FIG. 6 is a bottom view thereof.
